R. HART

TELEPHOTOGRAPHIC SENDING APPARATUS

Filed July 2, 1923

FIG. 1.

Inventor;
Russell Hart,
per
Arthur J. Farnsworth
Attorney.

UNITED STATES PATENT OFFICE.

RUSSELL HART, OF LOS ANGELES, CALIFORNIA.

TELEPHOTOGRAPHIC SENDING APPARATUS.

Application filed July 2, 1923. Serial No. 649,086.

To all whom it may concern:

Be it known that I, RUSSELL HART, a citizen of the United States, residing at Los Angeles, in the county of Los Angeles and State of California, have invented a new and useful Telephotographic Sending Apparatus, of which the following is a specification.

My invention relates to telephotography, and among its salient objects are; first, to provide improved means for modulating energy waves in such a way as to adapt them for the reproduction of drawings, photographs, printed matter, and the like, at a remote point by the methods of telephotography; second, to afford facilities for sending out this modulated energy either by radio, wired radio, or wired systems, as conditions may make most desirable; and, third, to accomplish the above results through the medium of relatively simple and thoroughly dependable apparatus. Other objects and advantages of my invention will appear hereinafter.

It is to be understood that, while I illustrate and describe herewith a preferred means for accomplishing my objects, I do not limit myself to the specific forms and arrangements disclosed. Various changes and adaptations may be made therein without departing from the spirit of my invention as hereinafter claimed.

My objects are attained by the apparatus illustrated in the accompanying drawing, which is to be considered as diagrammatic throughout, rather than strictly pictorial. In this drawing—

Figure 1 is a side elevational diagram of the arrangement of the mechanical and optical parts of my apparatus;

Figure 2 is a wiring diagram showing the circuits and connections of the electrical portions of the apparatus;

Figure 3 is a diagram illustrating the manner in which a radio frequency energy wave is modulated by my improved means;

Figure 4 is a diagrammatic view of a fragment of photographic film indicating the manner in which it is employed by me for photo-modulating energy;

Figure 5 is a side elevation of a preferred form of mounting for the photo-electric cell used as a necessary part of the equipment;

Figure 6 is a plan view of the above mounting, showing the manner in which it is made to traverse the photo-modulating field of operation; and—

Figure 7 and Figure 8 respectively are front and side elevational views of a preferred form of photo-electric cell for use in connection with my apparatus.

Similar reference numerals refer to similar parts throughout the several views.

The present invention concerns itself only with tele-photographic sending apparatus. It comprises; first, means for projecting strong images of the graphs to be transmitted upon a plane, and for causing these images to repeatedly move across the plane at a uniform speed; second, means for causing a photo-electric cell to move uniformly across the plane perpendicularly to the direction of motion of the images; and, third means for causing the cell to modulate a suitable electric current, or a suitable series of electrical impulses, in a manner that corresponds to the light variations in the images.

The photo-electric cell in effect is made to traverse the optical images in successive closely spaced parallel strips, ultimately covering substantially the whole areas of the images. By means of the variation of the light intensity falling upon the cell I thus produce continuously photo-modulated electrical energy that may be transmitted and utilized for distant photographic reproduction of the original images.

In the embodiment of my invention selected for illustrative purposes I employ a powerful source of illumination, such as the arc lamp 9, and by means of condensing lenses 10 I concentrate the light upon a moving transparent film 11 bearing the matter to be telephotographed. The light rays, after passing through the film, are focused by projecting lenses 12 on the plane 13 of an imaginary screen, so that graphical matter upon the film is projected as a greatly enlarged image upon this plane.

The film may be the ordinary form of photographic film used in the motion picture industry, or it may be a strip of tracing linen or other transparent or translucent material suited for the matter to be transmitted. The latter may be drawn, photographed or printed upon the film. This op-

tical film is made up in the form of a relatively short endless belt of definitely determined length, and having uniformly spaced perforations 14 at each of its edges for controlling its motion.

The film runs upon four, gear-driven, sprockets having pin teeth at each end for meshing with perforations 14. Two of these sprockets viz., 15 and 16, revolve about 10 axes perpendicular to the axis of lenses and on opposite sides thereof. The other two sprockets, viz., 17 and 18, have their axes in a plane parallel to the lens axis, and on one side thereof. The film in passing from one 15 set of these sprockets to the other takes a quarter turn, and is at the same time turned inside out, so that one side of the film runs upon sprockets 15 and 16, and the other side upon sprockets 17 and 18. This arrangement allows using a short length of 20 film belt and puts the return portion of the belt outside the path of the light rays, which thus pass through the film at the point 19 only.

25 Each of the four sprockets is provided with a pair of small spring constrained rollers 20, for keeping the film upon their respective surfaces, and in mesh with their sprocket teeth. This permits of using the 30 quarter turn inside-out twists 21, without danger of displacement or disengagement.

The film runs under slight tension through a pressure gate 22, where it intersects the light rays. Its continuous, relatively rapid, motion prevents burning at 35 this point, and the gate may be artificially cooled if desired. Uniform speed is imparted to the film by the synchronous motor 23, acting through the spur gears 24, and 40 bevel trains 25 and 26. These are diagrammatically depicted in Fig. 1.

A simple and satisfactory form of photo-electric cell is shown at 27, and most clearly in Figs. 7 and 8. This comprises a platinumized strip 28 on a glass cover plate 29, the strip being etched down to the glass in such a manner as to form a very fine interlaced grid 30, the two halves of which are not in contact. The interstices are then 45 filled with selenium or other photo-active material. The strips are provided with terminal wires 31, and the photo-active material is enclosed in a glass or porcelain cup 32 containing calcium chloride, cemented to 50 the back of the cover plate. Other forms of photo-active cells such, for example, as those depending upon photo-ionic phenomena, may also be used.

The photo-modulating device, as cell 27 60 here shown, is mounted on a carriage 33 adapted to slide upon a horizontal shaft 34, parallel to screen plane 13. The carriage is made with a threaded half nut portion 35 adapted to rest upon, and be engaged by the feed screw 36. By means of

the latter, the modulating device may be made to traverse the screen plane in a direction perpendicular to the direction of motion of the film images.

Feed screw 36 is positively driven by 70 motor 23, as by the worm and sprocket gearing indicated at 37. The carriage 33, when it has reached the end of its travel, may be quickly returned to its starting position 75 by lifting the half nut portion clear of the feed screw, and sliding it back on the shaft 34.

Flexible shaft couplings are indicated at 80 38, and are usually found to be a convenience in installation and to reduce vibration.

The various gearing ratios of the apparatus are so chosen that film 11 makes one complete revolution, that is it completes one complete cycle of its movement, coincidently 85 with one complete revolution of feed screw 36. Consequently the photo-electric cell is made to traverse the recurring moving images in plane 13 along lines corresponding to the dotted lines 39 in Fig. 4. The width of grid 30 may be made equal, or 90 nearly equal, to the pitch of feed screw 36, so that a sufficient number of revolutions of the film will result in having the photocell completely cover the whole area of the projected images. During this time the material of the cell grid is constantly subjected to varying light intensities, corresponding 95 to the relative densities of the matter on the film. This enables it to be used for modulating the transmitted electrical energy in a 100 manner that will now be described.

A typical arrangement of the electrical features of my invention, and the manner in which they may be connected, is illustrated in the diagram of Fig. 2. There are 105 three complete and separate groups of circuits indicated, viz; an energy modulating group at the left of inductive coupling 40; an amplifying group to the right of this coupling; and a transmission circuit inductively coupled to the amplifying group at 41.

The energy modulating group as here 110 shown, is made up of a re-generative oscillating circuit containing the photo-modulating means. This group comprises; a three-electrode thermionic tube 42; inductance 43; transformer 44; two variable capacities 45 and 46; filament battery 47; plate battery 48; photo electric cell 27; and primary coil 49 of inductive coupling 40.

The tube filament 50 is connected directly across battery 47. The tube grid 51 is connected through inductance 43, and coil 52 of transformer 44 in series, to filament 50. The tube plate 53 is connected through battery 48, photo-cell 27, primary coil 49 of inductive coupling 40, and coil 54 of transformer 44, in series, to filament 50. Capacity 45 shunts inductance 43 and coil 52, 125 130

Capacity 46 shunts the photocell 27 and primary coil 49.

The group of circuits just described constitutes a system that will oscillate vigorously and continuously, if the circuit constants are properly chosen, and the adjustments are properly made. The current in the plate circuit of the system, which includes photo-cell 27 and primary coil 49, is uni-directional, i. e., it is pulsating direct current. The photo-modulation of these radio-frequency direct current impulses consists in varying their amplitude in the manner indicated in Fig. 3, by the action of the photo electric cell.

It is well known that selenium, in common with similar photo-active substances changes its resistance greatly when acted upon by light rays. As here used the selenium is in the form of a sinuous filament of great tenuity, and relatively great length, bridging grid 30. A very large proportion of its substance is thus subjected to the action of the light rays, and it is very quick to respond to variations in the light intensity by changing its resistance. The direct current impulses passing this varying resistance are modulated in amplitude and we thus have, in effect, imposed an irregular light modulated energy wave 55 upon a uni-directional radio-frequency wave 56.

The amplifying group of circuits comprises; a three-electrode thermionic tube 57; secondary coil 58 of inductive coupling 40; primary coil 59 of inductive coupling 41; filament battery 60; grid battery 61; plate battery 62; variable capacity 63; grid leak 64; and rheostat 65.

The tube filament 66 is connected across battery 60 with rheostat 65 in series. The tube grid 67 is connected through grid battery 61, capacity 63, and secondary inductive coupling coil 58, in series, to the filament 66; and grid leak 64 is connected as a shunt between the grid and the filament. The tube plate 68 is connected to filament 66 through battery 62, and primary coil 59 of inductive coupling 41, in series.

This group of circuits amplifies the modulated energy wave received inductively through coupling 40, and delivers it, unchanged in form but increased in power, to the transmission circuit, through the medium of inductive coupling 41.

The transmission circuit receives its energy inductively through secondary coil 69 from the amplifying group of circuits, in the manner just explained. This energy is in the form of a relatively powerful radio-frequency wave of modulated amplitude. It can therefore be transmitted to a distant receiving station either by radio, wired radio, or wired circuits, by methods well known in this art. The terminals 70, of coil 69, are suitably connected to deliver the

energy to the type of transmission considered most desirable for meeting the conditions encountered.

The foregoing description will enable anyone who is familiar with the arts of radio-transmission and telephotography, as hitherto developed, to clearly understand the arrangement of the constituent elements of my invention, and co-ordination of their operation. Further description and elaboration of details is therefore considered superfluous. I desire however to call particular attention to the following advantageous features that might otherwise be overlooked.

The great magnification of the graphical images in plane 13 permits of the use of a photo-electric grid of practical dimensions which at the same time is so small in proportion to the size of the images that in relation thereto it corresponds to but a small point. The rectangular shape of the grid permits covering a very large percentage of the image areas, closely approaching the total area.

The location of the photo-electric cell far removed from the traveling film, completely obviates the effects of static electricity from this source, to which it might otherwise be subjected. Furthermore the location of the cell far distant from the light source, permits it to be operated at a much lower temperature than would otherwise be possible.

By the use of projected rays, and optical images, I entirely avoid the necessity for mechanical slits in contact with the film surface, and thus avoid the danger of abrasion, clogged slits, "chattering" films, and the other evils that the older method is subject to. The effects of slit refraction are also avoided.

An enormous amount of light may be concentrated upon the film in the pressure gate since, by reason of the relatively rapid motion of the film, it is not exposed to the high temperature long enough to become dangerously heated. The heat accumulated during the brief time of its exposure is radiated throughout the remaining, relatively great, portion of its cycle of revolution.

Finally I desire to point out that it is perfectly feasible to water-cool or otherwise cool the pressure gate, and also the photo-electric cell, if this should be found to be necessary.

I claim as my invention:

1. Apparatus of the character described comprising; means for projecting optical images upon a plane; an oscillating circuit including a photo-electric cell and an audion, whereby a photo-modulated current may be produced; and means for causing said cell to traverse said plane for modulating said current; said cell being connected in the plate circuit of said audion.

2. Apparatus of the character described

comprising; means for projecting optical images upon a plane and causing them to traverse it; an oscillating circuit including a photo-electric cell and an audion, whereby a photo-modulated current may be produced; and means for causing said cell to traverse said plane transversely to the direction of motion of said images for modulating said current thereby; said cell being connected in the plate circuit of said audion.

3. Apparatus of the character described comprising; a movable optical film with graphs thereon; means for projecting images of said graphs upon a plane; an oscillating circuit including a photo-electric cell and an audion, whereby a photo-modulated current may be produced; and means for causing said cell to traverse said plane transversely to the direction of motion of said film, for modulating said current; said cell being connected in the plate circuit of said audion.

4. Apparatus of the character described comprising; an endless rotatable optical film with graphs thereon; means for projecting

images of said graphs upon said plane; means for uniformly rotating said film to cause said images to traverse said plane; an oscillating circuit including a photo-electric cell and an audion, whereby a photo-modulated current may be produced; and means for causing said cell to traverse said plane at a uniform speed transversely to the direction of motion of said images, for modulating said current; said cell being connected in the plate circuit of said audion.

5. Apparatus of the character described comprising; means for projecting recurring optical images upon a plane and causing them to traverse it at a uniform speed in registering paths; an oscillating circuit including a photo-electric cell and an audion, whereby a photo-modulated current may be produced; and means for causing said cell to traverse said plane at a uniform speed transversely to the direction of motion of said images, for modulating said current; said cell being connected in the plate circuit of said audion.

RUSSELL HART.
